(57) **CLAIM**

The ornamental design for a switch plate, as shown and described.

DESCRIPTION

FIG. 1 is a top front and left side perspective view of an outer and inner frame assembly for a single switch plate showing my new design;

FIG. 2 is a front view thereof;

FIG. 3 is a top plan view thereof;

FIG. 4 is a right side view thereof, the left side being a mirror image thereof;

FIG. 5 is a rear view thereof;

FIG. 6 is a bottom plan view thereof;

FIG. 7 is a top front and left side perspective view of an outer and inner assembly for a double switch plate;

FIG. 8 is a front view thereof;

FIG. 9 is a top plan view thereof;

FIG. 10 is a right side view thereof which is a mirror image of the left side thereof;

FIG. 11 is a rear view thereof;

FIG. 12 is a bottom plan view thereof;

FIG. 13 is a top front and left side perspective view of an outer and inner assembly for a triple switch plate;

FIG. 14 is a front view thereof;

FIG. 15 is a top plan view thereof;

FIG. 16 is a right side view thereof which is a mirror image of the left side thereof;

FIG. 17 is a rear view thereof;

FIG. 18 is a bottom plan view thereof;

FIG. 19 is a top front and left side perspective view of an outer and inner assembly for a quadruple switch plate;

FIG. 20 is a front view thereof;

FIG. 21 is a top plan view thereof;

FIG. 22 is a right side view thereof which is a mirror image of the left side thereof;

FIG. 23 is a rear view thereof; and,

FIG. 24 is a bottom plan view thereof.
